UNITED STATES PATENT OFFICE.

GODFREY BAMBERG, OF LONDON, ENGLAND.

PROCESS OF MAKING DETERGENTS.

SPECIFICATION forming part of Letters Patent No. 700,602, dated May 20, 1902.

Application filed September 12, 1901. Serial No. 75,209. (No specimens.)

To all whom it may concern:

Be it known that I, GODFREY BAMBERG, a subject of the King of Great Britain, residing at Boswell House, Bolt Court, Fleet street, 5 London, England, have invented certain new and useful Improvements in Processes of Making Detergents, of which the following is a specification.

My invention has for its object the manufacture of a dry detergent powder, which shall be instantly and completely soluble in cold water, from oatmeal or the meal of other suitable cereal, olein, (commercial oleic acid,) and caustic soda of density sufficient to cause the 15 chemical change in the oatmeal and combination between the oleic acid and soda, which by subsequent absorption of carbonic acid shall produce a dry detergent powder of exceptional cleansing properties and the whole 20 of which manufacture and chemical reactions shall be carried on without the application of heat.

In carrying out my invention I put into a powerful mixer a charge of oatmeal or the 25 meal of other suitable cereal and add one-half of the entire charge of olein and run the mixer for about five minutes to thoroughly incorporate the meal and oil and then mix with it the remaining half of the oil. A 30 charge of caustic alkali in solution of density 1.375 to 1.4 specific gravity is now poured into the mixer and run for fifteen minutes, at the end of which time the whole of the 35 charges are converted into a friable solid material, which can be readily run through machine-sieves and granulated. Considerable 40 heat is evolved during the several chemical reactions which take place. The granules are placed on trays, and the free alkali thereof 45 absorbs carbonic-acid gas from the atmosphere, forming carbonate of soda, which carbonate takes up the water of the mixture as water of crystallization, the mixture becoming in the course of a week's exposure a dry 50 powder, which has increased in weight by its exposure from eight to ten per cent. The oatmeal - hulls are decorticated during the operation of the process, and the caustic alkali decomposes them to a soluble mass. The 55 powder when desired can now be ground and perfumed or an antiseptic, such as thymol, be added. This powder is completely solu-

ble in cold water and is far more cleansing than soap, the oatmeal being entirely changed in composition. 55

I find one of the best proportions in the charges for insuring the product shall be properly available for after process is as follows: oatmeal, eighteen pounds; olein, thirteen pounds; caustic soda, twelve pounds, 60 dissolved in water to be of density 40° Baumé. The weight of the water mixed with twelve pounds of caustic soda is twenty-two pounds, equal to two gallons and one quart. This will produce after the week's exposure to the atmosphere and taking up carbonic acid seventy-two pounds of dry soap powder. 65

When it is desired that sodium carbonate should not be present in the powder, before turning the product from the mixer a charge 70 of ammonium sulfate may be run in, so as to produce some sulfate of soda instead by the reaction with the free alkali present in the mixture before carbonation. A soap powder for toilet purposes can also be made by mixing with the oleine a dextrinized meal in suitable proportions and the alkali in proportion to exactly combine with the olein added and after working the mixer adding some odorless dextrine to bring the material to a condition 75 suitable for granulation and drying.

Instead of olein, cotton-seed or other oils, as free as possible from stearin or stearic acid, may be used; but the olein is the best suited for this purpose. 85

I declare that what I claim is—

1. A process of manufacturing a detergent powder consisting in mixing olein and a suitable cereal, then adding caustic alkali of suitable strength, and then exposing said mass 90 to the atmosphere until the free alkali becomes carbonated.

2. A process of manufacturing a detergent powder consisting in mixing in water olein and a cereal, adding an alkali thereto, and 95 then exposing the mass to the atmosphere for the purpose set forth.

3. A process of manufacturing a detergent powder consisting in thoroughly mixing a suitable cereal and olein, then adding to the 100 mixture and thoroughly incorporating therewith caustic alkali, and then suitably exposing the said mixture to the atmosphere.

4. A process of manufacturing a detergent

powder consisting in suitably mixing oatmeal and olein, then adding to the mixture and thoroughly incorporating therewith caustic alkali of a sufficient strength, and then suitably exposing the mixture to the atmosphere until the free alkali becomes carbonated.

5. A process of manufacturing a detergent powder consisting of mixing olein and oatmeal together, incorporating in the said mix-

ture an alkali, and then exposing said mass to the atmosphere, for the purpose set forth.

In testimony whereof I have hereunto set my hand in presence of two subscribing witnesses.

GODFREY BAMBERG.
